UNITED STATES PATENT OFFICE

OTTO BUTZBACH, OF CHICAGO, ILLINOIS

TUMBLER CONSTRUCTION

Application filed February 28, 1931. Serial No. 518,956.

My invention relates to laundry apparatus, and is more particularly concerned with the construction of the rotary type of tumblers or cylinders for laundry machines.

5 In all the cylinders at present employed in the various washing machines, dry cleaning machines and drying machines, the revolvable cylinder is provided with openings whereby the clothes are inserted or removed, 10 and which openings are adapted to be closed by doors.

The doors in common use today on laundry tumblers are of two general types, hinged doors mounted along the side of the cylinder 15 which swing outwardly and upwardly when they are opened, pivoting on suitable hinges on the cylinder, or sector-shaped sliding doors which slide in suitable guides provided on the tumbler cylinders. Both of these types 20 of doors are equipped with suitable locks to keep them closed during the clothes cleaning operation.

The principal difficulties in the successful use of doors of both of these types lie in the 25 fact that due to the rotation of the cylinder during operation, large bodies of clothes are periodically thrown against the door sections and eventually the hinges, the locks or the guides will wear under this continual pounding to a point where new hinges, guides or locks are required. Further, the edges of the 30 guides will become worn from this continuous pounding until a clearance exists between the guides and the doors, and clothes may become pinched between these parts and eventually be torn. Ofttimes the edges of side flanges of the doors or guideways are worn to a thin edge which cuts clothes within the cylinder and otherwise damages the clothes. 35 With these facts in mind, it is an object of my invention to provide an improved cylinder construction wherein all the above named objections will be eliminated.

An object of my invention is the provision 40 of an improved cylinder and door construction wherein hinges, guides and locks may be eliminated.

A further object of my invention is to provide an improved door for clothes cylinders.

A further object is to provide an improved door that may be used with either a wooden or metallic cylinder.

A further object is to provide an improved door that is adapted to open toward the inside of the cylinder. 55

A further object is to provide an improved cylinder construction equipped with a wedge-shaped door opening wherein a suitable door will be tightly secured and held in place by 60 the rotation of the cylinder.

A further object is to provide a door for a clothes cylinder provided with a wedge-shaped frame arranged to fit tightly into a wedge-shaped door opening in the cylinder 65 so that from the centrifugal force of the rotating cylinder the door will automatically be tightly fitted within the door opening.

A further object is to provide a door of this type which may be opened inwardly and 70 provided with suitable guides within the cylinder for directing the door to an open position.

A further object is to provide a door construction of this type provided with rounded 75 corners and so arranged to be fitted into the doorway opening that no wear is possible from which sharp corners or thin edges can evolve.

Other objects and advantages will be more clearly set forth in the accompanying specification, wherein reference is had to the accompanying drawings, in which

Figure 1 is a side elevational view of a 80 typical laundry machine tumbler or "cylinder" with a portion thereof broken away in cross section to more clearly show other parts thereof;

Figure 2 is a vertical sectional view taken 85 on the line 2—2 of Fig. 1;

Figure 3 is a plan view of my improved door;

Figure 4 is a perspective view of one end portion of the guide elements; 90

Figure 5 is a transverse sectional view through a portion of the tumbler, taken on the line 5—5 of Fig. 2 and looking in the direction of the arrows; and

Figure 6 is an end view of the door, a por- 100

tion thereof being broken away in section to more clearly show other parts thereof.

In the drawings, I have shown a cylinder 10, which may be of the general type of 5 revoluble, foraminated cylinder commonly used in drying machines. The cylinder 10 is formed with three clothes sections 12, 14 and 16, and comprises the end walls 18 and 20 and the dividing or partition walls 22 and 10 24. A cylindrical shell 26 is positioned between each of these walls. The shells 26 are provided at their ends with outwardly turned flanges 28. The shells are attached to the partitions and end walls by means of suitable rivets 30, which extend through these flanges and through the partitions or the end walls as the case may be. A centrally disposed stub shaft 32 is secured to each end wall, by means of which the cylinder 10 is 15 mounted for rotary movement. Means for rotating the cylinder may be attached to either shaft 32 in the usual manner well known in the art. The shells 26 are provided at suitable intervals with inwardly extending 20 ribs 34, by the use of which the proper tumbling of the clothes is produced.

A rectangular metallic door frame 36 is provided for each clothes section and is suitably positioned between a pair of the inwardly disposed ribs 34. The frame 36 may be of any desired construction, provided with inwardly diverging walls 38, and is adapted to be rigidly secured between the walls separating the compartments by rivets 37. The frames thus positioned provide door openings having outwardly converging walls forming in effect a wedge-shaped opening.

In each of the frames 36, one of my improved doors 40 is mounted. Each door 40 40 may comprise a closed rectangular frame 42 formed to simulate an angle iron and having its base element 44 horizontal and its upright leg 46 inwardly disposed. The frame 42 thus 45 formed is arcuately shaped, as shown in Fig. 2, to correspond generally to the circumference of the cylinder 10. A panel 48 is placed in frame 42 and secured thereto in any suitable manner, such as by the rivets 50.

50 A latching means 52 is mounted at one end of the door 40. This latch unit may be omitted in some forms of the invention and comprises a housing 54 secured on the panel 48. A locking bolt 56 is mounted in this 55 housing and has one end extending through an opening 58 in frame 42 and the other end pivotally connected through a sliding connection with a forked lever 60. Lever 60 is provided with a handle portion 64 and is 60 pivotally mounted upon a pin 62 secured to panel 48. Movement of bolt 56 by means of handle 60 will either retract or advance bolt 56 into an opening 66 in the door frame 36.

65 The door 40 is further provided with a pair

of lugs 68 secured to a side wall thereof opposite the latching means 52. These lugs 68 are adapted in a door closing position to loosely fit into openings 70 in the door frame 36.

It will of course be understood that the 70 openings 66 and 70 are considerably larger than the associated bolt 56 and lugs 68 so that from the effect of centrifugal force the door 40 may be moved outwardly beyond a normal door closing position, the position 75 thereof being governed by the movement of frame 42 within the tapered walls 38.

Means for supporting the door in an open 80 position is provided and may comprise the guide and supporting rails 72 fastened to the partitions and end walls by suitable rivets 74. The guide rails 72 may be in the form of angle irons, having rounded corners whereby clothes tumbling into contact with these rails will not be injured. It will be noted that the rails 72 extend from a point adjacent a rib 34 to a point adjacent the door frame 36, and the inwardly projecting flange 76 thereof is tapered inwardly at 78 to avoid a sharp corner at its meeting edge with the frame 36. Due to the many undesirable features of sharp corners or thin edges in the interior of a clothes tumbler, any sharp edges at the ends of the guide rails have been thus effectively eliminated.

90 In use, when it is desired to open the door 40, the lever 60 is grasped and swung upwardly to withdraw lock bolt 56, after which inward pressure upon the door will move the door to a rest position upon the guide rails 72, at which time the door may be moved upwardly upon the rails to the dotted line position shown in Fig. 2. In this position, the entire door opening is clear and clothes may be removed or placed within the revolvable cylinder 10.

95 My improved door construction eliminates the possibility of an upwardly swung hinged door falling upon the operator during a clothes loading or removing operation, thereby preventing possible bodily injury to the operator. Further, due to the wedging action of the four side walls of the door within the door frame, no clothes can possibly become entangled with the door or door frame, thus avoiding the possibility of tearing or twisting the clothes. The elimination of any sharp points or thin edges by this construction eliminates any possibility of tearing or cutting clothes during the tumbling process. 100 In view of the fact that the centrifugal action of the revolving tumbler will serve to solidly seat the door within its frame, no wear will occur at the door bolt or its opening. Consequently, these parts need never be replaced.

105 While I have shown and described my invention as embodied in a metal cylinder and a metal door and door frame, it will of course be understood that the same general features 110 may be incorporated in a cylinder and door 115

constructed entirely of wood or a wooden door and a metal cylinder, or vice versa, and it is my purpose to protect this invention as applied to either wooden or metallic cylinder construction.

While I have shown and described only a particular embodiment of my invention, it will of course be understood that various changes and modifications may readily be made in the construction thereof and I do not wish to be limited in any particular. Rather, what I desire to secure and protect by Letters Patent of the United States is:

1. In laundry apparatus, a revolvable cylinder having an opening therein, a rectangular frame mounted in said opening, a wedge-shaped door detachably fitting in said frame and adapted to be moved inwardly to an open position, and a pair of guide rails mounted within said cylinder adjacent the opening for guiding said door to an open or a closed position.

2. In laundry apparatus, a revolvable cylinder having a side opening therein, a rectangular frame mounted in said opening, said frame being formed with outwardly converging side walls, a door within said cylinder having similar converging walls adapted to detachably fit outwardly into said frame in a closing position, a latch and supporting lugs on said door for locking said door in said closing position in said frame, said door adapted to be opened inwardly into said cylinder and moved upwardly to uncover said opening, and guide and supporting means in said cylinder for supporting said door in an open position.

3. In laundry apparatus the combination of a hollow rotatably mounted receptacle having a door-opening through the periphery thereof, a door-frame mounted to surround the door-opening, a door detachably fitting in the door-frame and adapted to be moved inwardly to clear the door-frame and then laterally to clear the door opening, and means within the receptacle serving as the sole means for supporting the door in its lateral movements.

4. In laundry apparatus the combination of a hollow rotatably mounted receptacle having a door-opening through a wall thereof, a door-frame mounted to surround the door-opening, a door to fit into the door-frame from the inside of the receptacle, detachable connections between the door and receptacle for holding the door in the door-frame and to permit the door to be moved inwardly to clear the door-frame and then laterally to clear the door-opening, and a supporting guide within the receptacle serving as the sole means for supporting the door in its lateral movements.

5. In laundry apparatus the combination of a hollow rotatably mounted receptacle having a door-opening through a wall thereof, a door-frame mounted to surround the door-

opening, a door to fit into the door-frame from the inside of the receptacle, detachable connections between the door and receptacle for securing the door within the door-frame and permitting the door to be moved inwardly so that one edge thereof will clear the door-frame and then to be moved laterally to uncover the door-opening, and means within the receptacle serving as the sole means for guiding and supporting the door in its lateral movements.

In witness whereof, I hereunto subscribe my name this 16th day of February, 1931.

OTTO BUTZBACH.
